United States Patent Office

Des. 232,272

Patented July 30, 1974

232,272

TREE SEEDLING CARRIER

Philip F. Hahn, Eugene, Oreg., assignor to Georgia-Pacific Corporation, Portland, Oreg.

Filed Feb. 12, 1973, Ser. No. 331,580

Term of patent 14 years

Int. Cl. D3—99

U.S. Cl. D87—1 R

FIG. 1

FIG. 2

FIG. 3

FIG. 1 is a front perspective view of a tree seedling carrier embodying my new design;

FIG. 2 is a top view thereof; and

FIG. 3 is a bottom plan view thereof.

The rear face is the same as the front face.

I claim:

The ornamental design for a tree seedling carrier, as shown and described.
